UNITED STATES PATENT OFFICE.

ANDREW C. WOOD, OF CHICAGO, ILLINOIS, ASSIGNOR TO STEWART-WARNER SPEED-
OMETER CORPORATION, OF CHICAGO, ILLINOIS, A CORPORATION OF VIRGINIA.

ODOMETER-TRAIN-RESETTING DEVICE.

Application filed April 21, 1920. Serial No. 375,515.

To all whom it may concern:

Be it known that I, ANDREW C. WOOD, a citizen of the United States, and a resident of the city of Chicago, in the county of Cook and the State of Illinois, have invented certain new and useful Improvements in Odometer-Train-Resetting Devices, of which the following is a specification, reference being had to the accompanying drawings, forming a part thereof.

The purpose of this invention is to provide an improved construction in an odometer for re-setting the trip train to zero or to any desired point or for advancing it to any desired amount. It consists in the elements of construction shown and described, as indicated in the claims.

In the drawings:

Figure 1 is a plan view of a structure embodying this invention.

Figure 2 is a partly sectional front elevation of the same, section being made axially with respect to the operating shaft and the dial wheels.

Figure 3 is a section at the line, 3—3, on Figure 2.

Figure 4 is a section at the line, 4—4, on Figure 2.

Figure 5 is a view similar to part of Figure 4, showing a different position of the parts.

Figure 6 is a view similar to the right hand end portion of Figure 1, showing a slight modification.

Figure 7 is a partly sectional front elevation of the same.

Figure 8 is a section at the line, 8—8, on Figure 7.

This application presents a variation of the structure of my co-pending application No. 353,770, and is intended to present and claim some features of that construction generically, and to present and claim some features of variation as between the two structures. In many respects the construction of the two applications is the same and in this application these identical parts will be described only in general terms, reference being had to said pending application for more specific description of the features which are specifically claimed in that application.

The structure shown in the drawings comprises a standard for the counter dials, comprising right and left hand brackets, 20

and 30, respectively, and a center bracket, 40, which afford bearing for the central shafts as hereinafter described, and from which are extended certain auxiliary bearings and bracket members hereinafter mentioned for carrying certain auxiliary shafts and other parts. Also at the right hand side of the right hand bracket, 20, there is provided a boss, 21, centrally with respect to which the shaft, 2, is journaled, on which boss there is mounted and keyed fast, as seen at 22, the housing, 23, for the re-set gears, 24 and 25, and the cam spindle, 26; all of which are substantially the same as shown in my said co-pending application No. 353,770, except as hereinafter particularly distinguished therefrom.

The continuous indication dials, 50, and their mode of operation need not be particularly described, the same being fully shown and described and claimed in my said co-pending application, but the following features may be noted for the purpose of the present invention. These continuous indicator dials, 50, are mounted on an axle or fixed shaft, 1, which is supported rigidly by the left hand bracket, 30, and which obtains bearing in the intermediate bracket, 40. The fixed shaft, 1, is co-axial with the rotating shaft, 2, of the trip train upon which the trip train dials, 60, are carried; and the shafts, 1 and 2, are telescoped with each other for journaling the trip train shaft, 2, on the shaft, 1. As shown, the trip train shaft, 2, telescopes in an axial bore, 11, in the right hand end of the continuous indication train shaft, 1, and a coil spring, 3, in said bore re-acts for extending the total shaft-length—that is, for thrusting the shaft, 2, to the right—to a limit which is determined by the trip-re-setting shaft, 26, as hereinafter described. This out-thrust position of the trip train shaft, 2, may be regarded as the normal or running position of said shaft, being the position at which the device operates in indicating travel mileage; and the in-thrust which may be given to the shaft, as hereinafter described, is referred to as the re-setting position. The main or initial gear of the counter-train, 6, is driven by any suitable means represented by gear, 7, suitably journaled on the frame standards for intermeshing of the gear, 7, with said driven gear, 6, power being communicated, by means not shown, to the gear, 110

7. The gear, 6, is provided with a housing, 6^a, by which it is mounted fast on the shaft. 2. The initial or lowest denomination dial wheel, 61, in the form shown in Figures 1 and 2, is fast on the shaft, 2. The succeeding dials of higher denomination are loose on said shaft for rotation thereabout but are furnished with means for driving engagement therewith, consisting of a ratchet shoulder, 2^c, 10 with which said shaft is provided, extending along the entire length of said shaft from the left hand side of the initial dial wheel, 61, one wall of a key seat or channel being cut away so as to leave the other wall standing to form said ratchet shoulder for engagement with the spring key, 67, with which each of the dial wheels, 60, is provided, mounted in recesses, 60^a, in the right hand side of each of said dial wheels, as 20 shown in Figure 4. Each of the dial wheels, 60, has on the side toward the next following dial a continuously toothed or unmutilated gear, 51, whose teeth are in number a multiple of ten, and at the side toward the next preceding dial, said dials have each a mutilated gear, 52, and a delay or locking disk, 53. The mutilated gear, 52, has teeth for driving engagement throughout one-tenth of its revolutions, and the delay or locking disk 53, is correspondingly cut away at 53^a. At each conjunction of preceding and succeeding dials, a pinion, 54, is provided journaled on a shaft, 55, parallel to the shaft, 2, extending between the brackets, 30 and 40. This pinion is actuated by the toothed portion of the gear, 52, and is thereby rotated through one-tenth of each revolution of said gear, 52, and rotates the next succeeding gear, 51, and its dial through one-tenth of a revolution for each revolution of the preceding gear, 52, and its dial, 60. This effects the "carrying" from column to column. The pinions are held locked against rotation in the intervals between 40 their successive engagement by the mutilated gear, 52, by the co-operating periphery of the delay disk, 53, and the delay segment, 52^a, of the pinion hub, laterally adjacent to the toothed periphery thereof, in a manner well understood and requiring no particular description.

The ratchet shoulder 2^c, formed by the cut away channel, in the shaft, 2, faces in direction for rotating the dials for advanced indication; and thereby it will be seen that it results that the dials may be independently rotated in the same advance direction without hindrance by reason of the shaft and its said ratchet shoulder, the spring pawls riding back and dropping over said shoulder in such advance rotation of the dial.

The normal position of the several parts,—that is, the position at which they will stand in the ordinary action of the device for re-

cording mileage travel, is shown in Figures 1 and 2, viz., with the gear, 24, disengaged from the gear, 25, and the shaft, 2, at the extreme right-hand limit of its range of thrust, its rounded end, 2^b, being stopped in the conical cam recess, 26^c, of the spindle, 26, and the gear, 6, engaged with the driving gear, 7. For re-setting to zero or to any other desired point, the spindle, A, will be pulled up or forward to bring the gear, 24, 75 into mesh with the gear, 25, this movement of the spindle, operating, by the cam slope of the recess, 26^c, of the spindle, to crowd the shaft, 2, to the left the shaft-end snapping back into the minor recess, 26^d, of the 80 spindle. The amount of longitudinal movement, thus given to the shaft disengages the gear, 6, from the gear, 7, and leaves the entire trip train free to be operated independently of the driving means connected with the travel wheel whose rotation it is normally designed to record. Thereupon, the operator desiring to re-set the entire trip train to zero, or to any other number consisting of the same digit in all columns, will 85 turn the knob, A, in clock-wise direction, causing the shaft, 2, to revolve in the reverse direction, its shoulder, 2^c, picking up each of said dials as said shoulder reaches the spring dogs, 67, of the several dials which 90 are all positioned similarly with respect to the zero points of the dials, and thereby in one revolution or something less, all of the dials will be picked up and aligned as to their zero points, and may be rotated to 95 bring any other figure to the reading opening of the casing. If it is desired to set the dials to indicate any advance number, the operator will reverse the rotation of the knob, 26, turning it in anti-clock-wise direction, thereby rotating in advance direction the initial or lower denomination dial at the right, and through it by means of the carrying wheels, rotating similarly each succeeding dial until the desired number is indicated. A more expeditious method of re-setting to any considerably advanced number consists in setting the initial or lowest denomination dial at the figure desired and 100 with the finger engaging the periphery of the succeeding dials in their order, rotating them to the figures desired to be indicated by them respectively. It will be understood that in this operation the spring pawls, 67, ride back over the ratchet shoulder, 2^c, of 105 the shaft, and that the carrying action from each dial to the next following will occur in the regular manner but will in no manner interfere with afterward setting the succeeding dials to the desired figure by further 110 advance movement in the manner described.

It may be understood that when rotating all the dials together by the manual operation of the spindle, 26, and picking up the dials at the points at which they happen 115

to stand, as above described, for re-setting all the dials to zero by the one movement, the pinions, 54, will be rotated by their continuous engagement with the gears, 51; and 5 as teeth of the adjacent mutilated gears, 52, with the delay or locking disks, 53, come around to the pinions respectively, said teeth are liable to arrive out of registration with the teeth of the adjacent gear, 51, and may 10 stand as shown in Figure 8, aligned with the intervals between the teeth of said gear, 51, instead of with said teeth themselves. In that event, the pinions will be thrown out of mesh with the gears, 51, by the delay 15 or locking disks, 53, and unless the pinions could yield out of mesh with the gears respectively, the re-setting movement would be blocked. To accommodate such condition of 20 misalignment, the bracket, 62, which carries the pinions is pivotally mounted as shown at 62^b, a spring, 62^a, being provided coiled around the pivot shaft, 62^c, yieldingly holding the bracket up to a position for proper 25 meshing of the pinions with the gears, but permitting them to yield out of mesh when at the alignment of like numerals the misalignment of the teeth of the gears, 51 and 52, occurs.

Figures 6, 7 and 8 show a modification of 30 the construction described and shown in the earlier numbered figures. This modification consists in making the initial or tenths dial wheel, 61, not fixed on the shaft, A, but so keyed thereto for rotation therewith, but so 35 as to permit the shaft to slide through it, this being effected by providing this gear with the same sort of a spring key, 57, as the device shown in the other dial, and continuing channel which forms the ratchet 40 shoulder, 2^c, within said initial dial as a complete groove or key seat, that is, not cut away at one side so as to reduce it to a mere ratchet shoulder as in the remainder of the length of the shaft within the other dial. 45 In this construction the dials are not displaced laterally in the movement of the shaft, 2, for resetting, and on the contrary, they are positively stopped against lateral movement between the bracket, 40, and the 50 hub of the gear, 7, on the shaft, 55. In all other respects the operation of the device in the form shown in these Figures 6, 7 and 8,

is the same as already described in respect to the other figures.

I claim:—

1. In a counting mechanism and the like which comprises a main train shaft, and a series of decimal-successive counter wheels in laterally successive position thereon with the initial wheel of the series positively engaged with the shaft for rotation and the remaining wheels of the series mounted loose on the shaft for rotation, and which comprises also means for carrying from each decimal lower denomination wheel to the next higher denomination wheel in the advance direction of the lower denomination wheel, and regular means for rotating the shaft to rotate the lower denomination wheel in advance direction; one-way-positive engaging means for engaging the shaft with the wheels above the lowest denomination in the rotation of the shaft in reverse direction; means for disengaging the shaft from the regular advance driving means, and means separate from said advance driving means for rotating the shaft in either direction at will. 60 65 70 75

2. In the construction defined in claim 1, said driving means comprising a driven gear said driving means comprising a driven gear fast on the shaft for positively engaging the lowest-denomination dial wheel, said lowest denomination dial wheel being rigid with the shaft for all movements therewith, the remaining dial wheels being stopped longitudinally of the shaft between said lowest denomination dial wheel and said driven gear, whereby all the said dial wheels are carried together in a longitudinal movement of the shaft for disengaging it from the regular driving means. 80 85 90 95 20

3. In the construction defined in claim 1 foregoing, the one-way-driving means being a pawl-and-ratchet engagement consisting of a single ratchet shoulder on the shaft, and pawls carried by the loosely mounted dial wheels respectively, said ratchet shoulder extending continuously along the shaft within all the loosely mounted dial wheels. 95

In testimony whereof I have hereunto set 100 my hand at Chicago, Illinois, this 7 day of April, 1920.

ANDREW C. WOOD.
